OLIVER VALLANDIGHAM, OF ST. LOUIS, MISSOURI.

Letters Patent No. 88,237, dated March 23, 1869.

IMPROVEMENT IN CIGAR-DRIERS.

The Schedule referred to in these Letters Patent and making part of the same.

To all whom it may concern:

Be it known that I, OLIVER VALLANDIGHAM, of St. Louis, in the county of St. Louis, and State of Missouri, have invented a new and useful Improved Cigar-Drier, of which the following is a full, clear, and exact description, reference being had to the annexed drawing, making a part of this specification, in which—

Figure 1 represents a front elevation of my invention, with a portion in section.

Figure 2 represents a transverse sectional elevation of same.

Similar letters indicate like parts.

The object of my invention is to thoroughly and rapidly dry cigars after they are packed ready for market.

It consists of a wooden box, A, figs. 1 and 2, of convenient size, having an inner casing, b, of zinc, or other non-conducting metal, so arranged as to leave an air-streak, c, all round the box, between the wooden and metal casings.

This is provided with a door, d, and in appearance resembles the ordinary refrigerator.

Two ventilators, e e', fig. 1, e, fig. 2, in the front of the box, near the bottom, provided with slides h h', fig. 1, h, fig. 2, for closing them, open into the interior of the box, as shown in fig. 2, while a third ventilator, k, figs. 1 and 2, likewise provided with a slide, is arranged at the top of the box.

Through an opening in the bottom of the box, I pass a gas-tube, t, figs. 1 and 2, provided with an ordinary burner, v, having a common gauze cap, g, fig. 1.

A little above the burner is arranged a series of cross-pieces, 1, 2, 3, 4, &c., fig. 1, and 5, fig. 2, on which are placed, one on top of the other, the cigar-boxes filled with cigars, ready packed for market, and the ventilators being closed, and the gas lighted, the door is shut, and in a short time, according to the greenness of the cigars, they are completely dried, after which they require no more attention. If the heat becomes too great, it is only necessary to open the ventilators, to reduce it to the required intensity. If it is desired, for any reason, to use coal-oil instead of gas, I arrange sheet-metal piping, s, (copper being preferable,) on the inside of the box, as shown in figs. 1 and 2, attaching it firmly to the back of the box.

This piping, by means of the extension o, figs. 1 and 2, is connected with the open air, while, by means of the hinged joint n, figs. 1 and 2, the elbow p may be made to assume the positions shown in figs. 1 and 2. An ordinary coal-oil lamp, having a copper chimney, being placed on the bottom of the box, near enough to the opening to receive a due supply of air, the elbow n is turned down, so that its mouth covers the chimney, which is made to fit closely in it. Then, the lamp being lighted, all the smoke and impurities pass out the extension o, the heat being radiated into the box. The lamp may, if desired, be placed beneath the box; and the gas-pipe being turned back by means of a hinged joint, its chimney may pass up through the opening, and connect with the elbow.

The same apparatus may be fitted for oil and gas, or for either separately; and I do not intend to limit myself to the use of either alone, or both combined.

This apparatus may be used either in the house or out, and by it almost any degree of heat may be obtained, its intensity being under complete control by means of the ventilators, and, being adapted to either gas or oil, can be used everywhere. The air-streak between the casings completely removes any danger of fire.

What I claim as my invention, and desire to secure by Letters Patent, is—

1. The combination of the box A, inner casing b, burner v, gauze cap g, ventilators e, e', and k, all arranged, constructed, and operating substantially as and for the purpose shown and specified.

2. The combination of the box A, inner casing b, ventilators e, e', and k, piping s, and elbow p, of a cigar-drying apparatus, with an ordinary coal-oil lamp, all constructed, arranged, and operating substantially as and for the purpose shown and specified.

3. A cigar-drying apparatus, combining the devices above set forth, when constructed, arranged, and operating substantially as and for the purpose shown and specified.

OLIVER VALLANDIGHAM.
